UNITED STATES PATENT OFFICE.

PETER J. TRACY, OF HARTFORD, CONNECTICUT.

DOOR OPENING AND CLOSING MECHANISM.

Application filed July 8, 1924. Serial No. 724,787.

To all whom it may concern:

Be it known that I, PETER J. TRACY, a citizen of the United States, and a resident of Hartford, in the county of Hartford and 5 State of Connecticut, have invented new and Improved Door Opening and Closing Mechanism, of which the following is a specification.

My invention relates to the class of devices employed for opening and closing double doors, and an object of my invention, among others, is the production of a device or mechanism of this class that shall be simple in construction, easy of operation, and 15 little liable to get out of order or become disarranged.

One form of device embodying my invention and in the construction and use of which the objects herein set out, as well as others, 20 may be attained, is illustrated in the accompanying drawings, in which—

Figure 1 is a top view of a set of double doors provided with my improved mechanism, the doors being shown as open.

25 Figure 2 is a similar view showing the doors in their closed position.

Figure 3 is a projected fragment of the door shown at the right of Figure 1.

In the accompanying drawings the numerals 5—6 indicate the members of a set of double doors that are hinged in the usual manner to supports 7. Each of these doors has a jointed main lever pivotally secured at one end to the door, said levers each comprising sections 8—9 pivotally joined as at 30 10—11, these joints being each so arranged that when the levers are fully extended their pivots will be located slightly at one side of a line passing through the pivots 12—13, so 35 that force applied to the doors to close them, when the levers are in this position, will be resisted by reason of the fact that such force will tend to swing the levers further in the same direction as that which took place 40 when the doors were swung to their open position. The pivot 13 is a fixed pivot secured to a stationary support (not shown) and each of the sections 8 of the lever are joined by toggle levers 14—15, each of which is 45 pivotally secured at one end to a section 8 of the main lever and at its opposite end each toggle lever is secured to the other lever.

50 A controlling lever 16 is pivotally secured at one end to the pivot 17 connecting the toggle levers, and at its opposite end the

lever 16 is secured to a fixed support (not shown) by a pivot 18.

A releasing cord 19 is secured at one end, preferably to one of the pivots of the joint of the main lever, as to the joint 11, and this 60 cord passes through an eye 20 located near the back edge of the door 6, and from said eye the cord passes through another eye 21 located near the front edge of the door, and from said eye downwardly to a position accessible for the purpose of operating it to release the joint 10 of the lever 7.

In operation the cord 19 is grasped at its lower end and a pull exerted thereon. This will "break" the joint 11 so that the door 6 70 may be swung inwardly, and this inward movement of the door will operate the main lever connected therewith so that the section 8 thereof will move the toggle lever 15 in a manner to exert a pull upon the toggle 75 lever 14, and this operation will "break" the joint 10. As the door 6 is swung to its closed position the connections comprising the several levers will also operate to close the door 5, the levers in the closed position of 80 the doors assuming the position shown in Figure 2 of the drawings.

In accordance with the provisions of the patent statutes I have described the principles of operation of my invention, together 85 with the device which I now consider to represent the best embodiment thereof; but I desire to have it understood that the device shown is only illustrative and that the invention may be carried out by other means 90 and applied to uses other than those above set out.

I claim—

1. A pair of doors, a jointed main lever pivotally secured at one end to each door with the intermediate pivoted ends secured to a fixed support, a pair of toggle levers each pivotally secured at one end to one of said main levers and at its opposite end to the other toggle lever, and a controlling lever 95 for restraining and controlling the movement of said toggle levers and having the end thereof spaced from the toggle levers pivotally secured to a fixed support.

2. A pair of doors, a jointed main lever pivotally secured at one end to each door and at its opposite end to a fixed pivot, the joint of one of said levers having a shoulder to lock it when its pivot has moved to a position in a straight line extending between 100 105 110

the pivots of the opposite ends of said lever, a pair of toggle levers each pivotally secured at one end to one of said main levers and at its opposite end to the other toggle lever, 5 means for restraining and controlling the movement of said toggle levers, and means for "breaking" the joint of the main lever.

3. A pair of doors, a jointed main lever pivotally secured at one end to each door 10 and at its opposite end to a fixed pivot, a pair of toggle levers each pivotally secured at one end to one of said main levers and at its opposite end to the other toggle lever, a controlling lever pivotally attached at one

end to said toggle levers, and a fixed pivotal 15 support for the other end of said controlling lever.

4. A pair of doors, a jointed main lever pivotally secured at one end to each door and at its opposite end to a fixed pivot, a 20 pair of toggle levers each pivotally secured to one end to one of said main levers and at its opposite end to the other toggle lever, and a controlling lever pivotally secured at one end to the joint connecting said toggle 25 levers and pivotally secured at its opposite end to a fixed support.

PETER J. TRACY.
